UNITED STATES PATENT OFFICE.

ALFRED H. KIDNEY, OF ORANGE, NEW JERSEY.

MAGNETIC SEPARATOR.

1,137,492.

Specification of Letters Patent. Patented Apr. 27, 1915.

Application filed August 18, 1914. Serial No. 857,380.

To all whom it may concern:

Be it known that I, ALFRED H. KIDNEY, a citizen of the United States, residing at Orange, in the county of Essex and State of New Jersey, have invented certain new and useful Improvements in Magnetic Separators, of which the following is a specification.

This invention relates to an improvement in magnetic separators, and the object is to provide an instrument which can be manipulated easily and readily, and can be used in testing magnetic sands carrying platinum and gold preliminary to concentration.

This invention relates to the use of the well-known horse-shoe type of magnet, and to obviate the difficulty encountered in removing particles from the bearing face or ends of the magnet, I have provided means for removing the particles or grains from the magnets.

The invention relates to still other novel features of construction and combinations of parts which will be hereinafter more fully described and pointed out in the claims.

In the accompanying drawings: Figure 1 is a view in side elevation of the invention; Fig. 2 is a similar view showing the shield in its lowered position; Fig. 3 is a longitudinal vertical sectional view of the shield; Fig. 4 is a detail view of the guide blocks, and Fig. 5 is a view in edge elevation showing a slightly modified form.

The magnet A is preferably of the standard hand horse-shoe type, in which the poles 1, 1 taper inwardly. On the inner side of the poles are channels or recesses 2, 2. A shield B is adapted to be fitted over the lower end of the magnet, and over each pole 1, the upper portion 3 of the shield being of a diamagnetic material, while the lower portion 4 of the shield is of a paramagnetic material, and which can be readily energized by the poles when the poles are brought into contact therewith. The lower portion 4 is constructed so that all four sides of the poles will engage the bottom, producing a greater area for attracting the particles. A recess 5 is formed centrally of the lower portion 4 of the member B, so that a greater attracting area is produced.

Connected to the shield B is a loop handle made of spring metal 6, which loop handle carries U-shaped guide members 7, 7 which are received in the channels 2. A disk 8 is

inserted in the upper end of the handle 6, and is fastened thereto by means of a screw 9.

In the modification shown in Fig. 5, the disclosure is the same as in Figs. 1 and 2, with the exception of the pins 10, which are substituted for the recesses 2—2. These pins 10, 10 form a means for limiting the movement of the guide members 7, 7.

The operator grasps the disk 8 of the handle when it is desired to operate the shield B. When the shield B is moved to the position shown in Fig. 1, the lower portion of the shield would be energized by the poles 70 of the magnet, and the particles will be attracted to the shield. When it is desired to remove the particles, the handle 6 is forced downwardly, to the position as shown in Fig. 2, bringing the poles within the upper 75 portion 3 of the shield, B, which is incapable of being energized, thereby deenergizing the lower portion 4 of the shield, so that the particles will fall readily from the shield.

The channels or recesses 2 control the 80 movements, that is, the lower ends of the channels limit the downward movement of the handle, and the upper ends of the channels limit the upward movement of the handle.

I claim:

1. The combination with a magnet having poles, of a shield mounted thereon, means carried by the magnet connected to the shield for moving the shield whereby the 90 contact will be made between the shield and poles for energizing the shield to attract particles, said shield adapted to be disengaged from the poles whereby the particles will automatically fall from the shield, and 95 means for controlling the movement of said shield.

2. The combination with a magnet having poles, of a shield mounted thereon provided with a contacting surface, a handle connected to said shield for causing the shield to be brought into engagement with the poles for the energization of the shield and for breaking the contact between said shield and poles, means on the handle having sliding engagement with the magnet, and means for limiting the movement of said sliding means for controlling the movement of the handle.

3. The combination with a magnet having poles, of a shield movably mounted on the 110 poles and provided with a contacting surface adapted to be brought into engagement

with the poles for the energization of the shield, a loop handle connected to said shield for making and breaking the contact between the shield and magnet, a disk mounted on the handle whereby the handle can be gripped for operating the shield, guides connected to the handle having engagement with the magnet, and means on the magnet

for limiting the movement of the members and handle.

In testimony whereof I affix my signature, in the presence of two witnesses.

ALFRED H. KIDNEY.
